UNITED STATES PATENT OFFICE.

ANGUS MacPHEE, OF LONDON, ENGLAND.

POWDER-RECEPTACLE.

No. 905,725.

Specification of Letters Patent.

Patented Dec. 1, 1908.

Application filed October 12, 1907. Serial No. 397,129.

To all whom it may concern:

Be it known that I, ANGUS MacPHEE, a subject of the King of England, residing at London, England, have invented new and useful Improvements Relating to Powder-Receptacles, of which the following is a specification.

My invention relates to that class of powder receptacles that are fitted with a spring-controlled dispensing head comprising a movable cap or cover seated upon a closed tubular neck, and my object is to simplify the construction of said head and provide the same with means for loosening the powder therein, so that, while cheapening the manufacture of such head, a greater reliability is insured for delivering the powder in loose quantities rather than caked lumps. I obtain this object by the arrangement of parts illustrated in the annexed drawing, in which:

Figure 1 is a portion of a receptacle provided with my improved head which latter is shown in section in its open position; Fig. 2, is a corresponding section showing the head closed; Fig. 3, is a cross-section on the line A—A of Fig. 1; Fig. 4, is an external view of the cap detached; Fig. 5, is a part-section of the cap applied to a cartridge tube; Fig. 6, shows a removable head secured to a jar; Fig. 7, is a modification to Fig. 6; and Fig. 8 shows a different manner of attaching the head to a jar or tin-box.

In all the figures, similar parts are marked by the same reference letters.

Referring first to Figs. 1 to 4, *a* denotes a metallic powder receptacle having a neck *b* closed at the upper end and formed with a plurality of lateral holes *c* preferably elongated as shown. These holes may be distributed all round the neck or only over half its surface. Furthermore, there is a rectangular hole *d* formed in the side of said neck.

The movable cap *e* has oval orifices *f* and a rectangular orifice *g* adapted to register with the orifices *c* and *d* respectively, the material from the orifice *g* being partially cut and then bent inward so as to form a tongue *h*. This tongue forms a guide and stop that prevents the cap turning upon the neck and at the same time limiting its endwise motion; thus obviating in a simple manner the necessity of providing special means for these purposes. Moreover, the tongue *h* also serves

as a stirrer to loosen the powder which often has a tendency to cake and fall out in lumps. 55 The cap is furnished with the usual internal spring *i* which normally forces it outward, thereby closing the orifices.

The receptacle can be filled through an aperture in the lower end which is closed by 60 means of a plate pressed into the rim of said aperture after a well known manner.

The cartridge in Fig. 5, is formed with a head like that shown at Figs. 1 and 2, and with a plain tubular body *k* closed at the 65 other end by a tight fitting cap *l*, or in any other convenient manner.

For powder jars and the like as shown at Figs. 6 and 7, I provide a separate dispensing head constructed after the manner of that 70 previously described and having a tubular prolongation *m* with a collar *n* which is fitted in a stopper *o* in the neck of the jar *p*. Or in lieu of the tubular portion and collar, I may adopt a tapering prolongation *q*. 75

In some instances I may dispense with the oval orifices, but in all cases the rectangular orifice with its tongue is provided.

According to the arrangement shown in Fig. 8, the head may be formed with an enlarged shoulder portion *r* having an inner 80 downwardly projecting rim *s* furnished with a packing ring *t* of suitable material so as to insure a tight joint in the top of a tin box *u* or the like. 85

What I claim and wish to secure by Letters Patent of the United States, is:

In a powder receptacle, the combination of a top having a projecting tubular neck, an aperture in the side of said neck, a cap fitting over said neck, a coiled spring between the top of said neck and the cap, a portion of the side of said cap being partially severed and the tongue thus formed being bent inward through the apertures in the neck to form a 95 stop to limit the upward movement of the cap and the aperture in the cap formed by such tongue registering with the aperture in the neck when the cap is depressed, as set forth. 100

In witness whereof I have hereunto set my hand in presence of two witnesses.

ANGUS MacPHEE.
